CLAIM

The ornamental design for an electrosurgical handpiece with activator, substantially as shown and described.

DESCRIPTION

FIG. 1 is a perspective view from the front/left of one form of an electrosurgical handpiece with activator;

FIG. 2 is a perspective view from a different angle to show the back and rear of handpiece with activator of FIG. 1; and, FIG. 3 is a side view of the handpiece with activator of FIG. 1.

The dashed line article shown at the rear of the handpiece is part of a cable which is not part of the claimed article.

1 Claim, 3 Drawing Sheets

FIG. 2

FIG. 3
